UNITED STATES PATENT OFFICE.

CHARLES ADAMS YOUNG, OF BRISTOL, AND JOSEPH HENRY WOODINGTON, OF CLEVEDON, ENGLAND.

MACHINE FOR FIXING HEELS TO BOOTS AND SHOES.

Application filed May 10, 1922. Serial No. 559,852.

To all whom it may concern:

Be it known that we, CHARLES ADAMS YOUNG and JOSEPH HENRY WOODINGTON, subjects of the King of Great Britain and 5 Ireland, and residents, respectively, of Bristol and Clevedon, both in the county of Somerset, England, have invented a certain new and useful Improvement in Machines for Fixing Heels to Boots and Shoes, of 10 which the following is a specification.

The present invention relates to a machine for fixing heels to boots and shoes, hereinafter jointly referred to as shoes, in the course of manufacture.

15 Hitherto in fixing high shaped heels to ladies' shoes, the last on which the shoe is made is withdrawn to enable the heel to be pinned on by a machine, and the last then re-inserted for the further operations required in the finishing of the shoe.

20 Further, under existing methods of fixing some heels of peculiar shape, such as Louis and the like, only a small part of the heel is in firm contact with the shoe.

25 According to this invention it is not necessary for the last to be withdrawn. The heel is cemented on the surface of its seat, placed in position, and held under pressure by the machine till such time as the cement 30 has set.

This effects a great improvement, the whole of the seat of the heel firmly adhering to the shoe; a further advantage being obtained by obviating the withdrawal of the 35 last and re-inserting the same whilst the shoe is in a damp condition, thereby saving time and possibly injury to the shoe.

Further, with a machine as hereinafter set forth, no marking or damage by the adjacent metal parts of the machine occurs on the sides of the shoes, as at present obtains 40 with existing machines.

In order that the invention may be the more readily understood, reference is to be 45 had to the following description and accompanying sheets of drawings, wherein:—

Figure 1 is a side view of a machine constructed in accordance with the invention, the movable parts of said machine being 50 shown in inoperative positions.

Figure 2 is a side view, the heel and top piece fixing members being shown in action.

Figure 3 is a similar view but showing

both heel and top piece and cemented extension fixings in action.

55

Figure 4 is a plan view of said Figure 3, the shoe and last being omitted for clearness.

Figures 5 and 6 are, respectively, front and end views of the machine, the shoe and 60 last also being omitted for clearness.

Like numerals of reference indicate corresponding parts in the several figures.

In carrying out the invention, the machine comprises a base plate 1 provided with 65 a centrally disposed pillar 2, to the upper end of which a last pin 3 is fixed, Figures 1, 2 and 3, and at the front end with a locking post 4, said post 4, which is in alignment with the pillar 2, having ratchet teeth 70 5 on its front edge, whilst at the other end of the base plate 1 there is provided another post 6, said pillar 2 and posts 4 and 6 being arranged vertically in relation to the base plate 1 and forming an integral part 75 thereof.

A frame-shaped lever 7, with handle 8 at its front end, is pivotally mounted by its slotted rear end to the rear post 6, and a self-acting pawl 9 is pivotally mounted in a 80 slot 10 in the handle 8, said pawl 9 engaging, when required, in the ratchet teeth 5 of the locking post 4.

A cross bar 11, the length of which corresponds to the width of the frame-shaped 85 lever 7, as in Figures 4, 5 and 6, is by its ends rigidly fixed to the upper ends of two metal straps 12, the other ends of said straps being pivotally secured to the side members of the lever 7 in a midway position therein. 90

A long screw 13 with a milled head 14 is screwed into a central and screw-threaded hole 15, Figures 5 and 6, in the cross bar 11, said screw 13 having a centrally disposed hole therein extending from end to end 95 thereof, and in said cross bar 11 two other holes 16 are provided, one on each side of and in alignment with the central hole 15 in a longitudinal direction.

A plate 17 located below the cross bar 11 is provided with three vertically disposed pins 18, suitably spaced apart to correspond to the holes 16 in the cross bar 11 and in the screw 13, and of said pins 18, which pass easily through said holes, the centre pin 18 100 is longer than the side pins 18, and is at its 105

upper end screw-threaded to take a nut 19 and thus hold the plate 17 to the cross bar 11, the side pins 18 acting as guides to keep said plate 17 in relative position to the top 5 of the heel of the shoe when in action.

This plate 17, which is the presser plate, is provided with a rubber pad 20 and can be raised or lowered by operating the head 14 of the screw 13, the object being to allow 10 for the different heights of heels, and a short stiff compression spring 21 is placed around the centre pin 18 and between the end of the screw 13 and the top of the presser plate 17 before the pins 18 are passed 15 through the cross bar 11 and screw 13.

Some shoes have heels which have a cemented extension of the sole of the shoe, and it is essential that this cemented extension be held under pressure against the 20 breast of the heel until the cement has set.

To enable the machine to effect this, and at the same time of operations, a second frame-shaped lever 22, with a vertical extension 23 to each side member thereof, is 25 pivotally secured above the lever 7 to the post 6, said lever 22 being provided with a handle 24 and self-acting pawl 25 to engage the ratchet teeth 5 of the locking post 4 in the same manner as obtains with the lever 7.

30 A flexible pad is connected to the lever 22 and the vertical extension 23 thereof by expansion springs 26 in the required position. The flexible pad consists of several pieces of thin spring steel of about half an inch in 35 width, and of various lengths, a short piece 27 being bent to correspond to the upward curve of a Louis or other heel front or breast. The other pieces 28 are riveted to this curved piece 27 side by side and cross-wise to it and are bent in such a manner 40 that they form a curvature across the upward curve of said short piece 27. A pad 29 of felt is secured to these steel pieces and so forms as a whole a flexible pad which adapts 45 itself to the various curves of the Louis or other heel front in either direction, when under pressure, without any parts touching the sides of the shoe.

The expansion springs 26 are connected to 50 the ends of the spring steel pieces 28, the other ends of said expansion spring 26 being connected to the frame-shaped lever 22 and the vertical extensions 23 thereof which sustain the flexible pad as a whole in the machine and in a suitable position for its 55 operation.

In use, the shoe 30 with the last 31 in it is placed on the last pin 3. Figure 1, fixed to the centre pillar 2 of the base plate 1. 60 The heel 32 is cemented on the surface of its seat and placed in position on the shoe 30. The top piece 33 is also cemented and placed on top of the heel 32. The lever 7 is held by the handle 8 and raised, and the 65 adjustable presser plate 17 carried by the

cross bar 11 is then swung over and placed on the top piece 33 of the heel 32 as in Figure 2 and the screw 13 manipulated according to requirements. The lever 7 is then forced downwards against the action of the 70 spring 21, bearing on the presser plate 17, the self-acting pawl 9 engaging the ratchet teeth 5 of the locking post 4, holding the heel 32 to the shoe 30 under pressure until the cement has set. 75

In the case of heels that have a cemented extension 34, Figures 1 and 2, of the sole up the front of said heel, the lever 22 is swung over, as in Figures 3, 4, 5 and 6, carrying the flexible pad on to the cemented 80 extension 34 and against the heel front. The lever 22 is then forced downwards against the action of the springs 26 connecting the pad to it, the flexible pad as a whole automatically adjusting itself to the heel front 85 and held there by the engagement of the pawl 25 with the ratchet teeth 5 of the locking post 4 in the same manner as obtains with lever 7, the cemented extension being held under pressure until the cement has set. 90

If desired, the machine can be used for fixing heels and top pieces only, or for fixing the cemented extension of the sole to heel front only, or for both operations at the same time. Either of the levers 7 and 95 22 can be readily removed from or fixed to the machine as required, said levers 7 and 22 being pivotally mounted on the pivot post by bolts and wing nuts 35.

To release the shoe from the machine, the 100 levers 7 and 22 are slightly depressed, pawls 9 and 25 drawn out of engagement with the locking post, and then swung over away from the shoe as shown in Figure 1, and the shoe and with it the last removed from 105 off the last pillar.

We claim:—

1. A heel affixing machine including a base, a last pillar supported thereon, a pair of lever elements pivotally supported one 110 above the other at one end of the base, presser means carried by one of said levers, a flexible pad carried by the other of said levers, and means for independently locking each lever in its operative set position. 115

2. A heel affixing machine comprising a base plate, a centrally arranged last pillar thereon, a pivot post carried by one end of the base plate and a locking post carried by the other end thereof, a pair of bifurcated 120 lever elements having their front ends formed to provide handles and pivotally supported at their rear ends in superposed relation on the pivot post, a pair of straps extending upwardly from the lower of said 125 levers, a presser plate carried by the upper end of said straps, a flexible pad yieldingly connected to the upper lever, and means carried by each lever for engaging with the locking post. 130

3. A heel affixing machine comprising a base plate, a pivot post arranged at one end of the base plate and a locking post arranged at the other end thereof, a vertical last pillar arranged between the pivot post and the locking post, a pair of open lever elements pivotally secured one above the other to the pivot post and carrying locking detents for engaging with the locking post 5 at their swinging ends, the upper lever being of less width than the lower lever thereby to permit the upper lever to nest within the lower lever when both levers are in operative position, presser means pivotally carried by 10 the lower lever, and a flexible pad yieldingly connected to the upper lever.
4. In a heel affixing machine, a pivot post, a last pillar, a pair of framed levers secured to the pivot post in superposed relation 15 whereby the levers may swing in opposite directions toward the last pillar to operatively engage with the heel of a shoe thereon, a locking post, an adjustable and yieldable presser plate operatively connected with one 20 of said levers thereby to elevate the same and hold it in engagement with the locking post, and a flexible pad carried by the other of said levers and yieldingly connected therewith, and a locking member carried by said 25 last-named lever and adapted to engage with the locking post thereby to place the yielding connections between the pad and lever in tension.
5. A machine for fixing heels and top 30 pieces also extension of sole to heel front of boots and shoes, including in combination a base plate with vertical and centrally disposed last pillar thereon, a pivot post to the rear end of said base plate, a locking post to the front end of said base plate, a lower 35 framed lever pivotally mounted on the pivot post, an adjustable presser plate pivotally carried by said lower framed lever, an upper framed lever pivotally mounted on the pivot post, a flexible pad resiliently supported from 40 the upper framed lever, and means for locking said upper and lower framed levers to the locking post.
6. A machine for fixing heels and top 45 pieces also extension of sole to heel front 50 of boots and shoes, including in combination a base plate, a last pillar, a pivot post and a locking post thereto, a framed lever pivoted to the pivot post, straps pivotally connected to the framed lever, a cross bar fixedly 55 carried by said straps, an adjustable presser plate carried by said cross bar, a framed lever pivoted to the pivot post in a position above said first framed lever, vertical extensions to said second framed lever, a flexible 60 pad connected by expansion springs to said extensions and framed lever thereof, and means for locking said framed levers to the locking post.

In testimony whereof we have affixed our 65 signatures hereto this 21st day of April, 1922.

CHARLES ADAMS YOUNG.
JOSEPH HENRY WOODINGTON.
